CLAIM

The ornamental design for a star and moon projection light, as shown and described.

DESCRIPTION

FIG. 1 is a first perspective view of a star and moon projection light showing our new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof; and,

FIG. 8 is a bottom view thereof.

The broken lines shown in the drawings depict portions of the star and moon projection light in which the design is embodied that form no part of the claimed design.
